UNITED STATES PATENT OFFICE.

CHARLES FRANCIS JENKINS, OF WASHINGTON, DISTRICT OF COLUMBIA.

MOUNTING FOR PICTURE-PROJECTING LIGHTS.

Application filed July 18, 1918. Serial No. 245,484.

To all whom it may concern:

Be it known that I, CHARLES FRANCIS JENKINS, a citizen of the United States, and resident of Washington, in the District of Columbia, have invented certain new and useful Improvement in Mountings for Picture-Projecting Lights, of which the following is a specification, reference being had therein to the accompanying drawing.

10 In the motion picture art it is now common to use for illumination incandescent electric lamps of high candle power, the light being produced by coiled filament having short segments extending back and forth 15 in a plane. Such lamps are obtainable commercially, and as made they are provided with the usual large screw threads so that they can be screwed into a standard socket. If the light from such a lamp is to pass 20 through a lens, the latter should obviously be parallel to the plane of the incandescent filaments and should have its optical axis perpendicular to that plane at its middle point or the middle point of the illuminating 25 area.

In motion picture machines this axis should pass approximately through the middle of the exposure opening, and hence the lamp should be vertically adjustable, for 30 properly framing the picture, while the illuminating filament is always in the proper plane whatever its adjustments. This is usually a matter of some difficulty, involving the adjustment of many parts. The 35 general objects of this invention are to provide for quickly adjusting a common lamp while keeping its filament in a single plane, and also for putting the lamp into the lighting circuit, or removing it therefrom, almost 40 instantly.

In the accompanying drawings,

Figure 1 is a side elevation of a lamp arranged in accordance with this invention, some parts of the lamp-house and lamp support being shown in section.

Figure 2 is a plan view of a portion of the same devices the lamp itself being omitted.

In these views, A represents an insulating plate sliding in ways A' in an ordinary lamp-house, and B a non-threaded, conducting lamp socket supported from the plate by a conducting bar C. D represents a high power electric lamp of the incandescent

type, having the usual socket-fitting threads at E and a terminal in the middle of its end face. Against this terminal normally presses a strong conducting spring F fixed to the plate A and adapted to follow the lamp through a very considerable vertical distance as the lamp is varied in height. 55 The socket is usually of spring metal and is longitudinally divided along one side and provided with normally separated, outwardly projecting lugs G through which passes a manually operated bolt H by which 60 the lugs may be drawn together causing the socket to grip the lamp.

The conducting bar C and the spring F are in electrical connection with springs or terminals I, I', respectively, carried below 70 the plate and so arranged that sliding the plate forward in its ways pushes the lamp terminal connections over the inclined ends or end portions of the springs I, I', thus 75 putting the lamp into the illuminating circuit by the mere act of sliding it to position.

The bolt H being so far loosened that the threaded portion of a lamp may slide directly into the socket, a lamp with its filament in the proper plane is placed therein 80 and pressed down, the spring F yielding, until the light beam passes properly through the exposure aperture, and then the lamp is clamped by tightening the bolt H. Slightly loosening the bolt allows the spring, or the 85 hand, or both, to raise the lamp if it has been pushed down too far.

It may be noted that the adjustment is quicker and easier than adjusting by rotation a lamp which can be so adjusted, that 90 is a lamp which lacks the large plane illuminating area.

Obviously the exact construction need not be followed.

What I claim is:—

1. The combination with supporting members provided with ways, of an insulating plate sliding in said ways, a compressing lamp socket having an internally smooth cylindrical surface, supported from the plate and provided with a terminal through which circuit may be made through the socket as the plate slides and broken by opposite sliding.

2. The combination with a supporting structure provided with ways, of an insulat-

2
ing plate slidably mounted in said ways and bearing a conducting lamp socket provided with a terminal and adapted to hold an axially sliding lamp, a conductor mounted alongside the path of said terminal in position to make and break contact therewith as the plate slides back and forth in its ways,

and a yielding contact member arranged to make contact with the central terminal of a lamp in said socket and maintain such contact when the lamp is vertically adjusted. 10

In testimony whereof I hereunto affix my signature.

CHARLES FRANCIS JENKINS.
